UNITED STATES PATENT OFFICE.

AARON J. MIRSKI, OF NEW YORK, N. Y.

MANIFOLD RECORD BOOK

Application filed March 5, 1925. Serial No. 13,057.

My present invention relates to new and useful improvements in combined recording books for repairmen or the like and customers' receipts and tags for identifying 5 articles left for repair or similar purposes.

The object of my invention is to provide a device of the character described so arranged that at a single entry, a permanent record will be had in book form of all 10 pairs or articles left for repair and at the same time provide an identification tag and customer's receipt.

A still further object of my invention resides in the provision of an arrangement of 15 a plurality of identifying tags and customers' receipts in bound form in connection with duplicate record sheets, and further resides in the manner of combining and arranging the same so as to quickly and efficiently and with the minimum amount of 20 manipulation of the parts thereof, serve their intended function.

More particularly, my invention has for 25 its object the provision of a storage battery repair and service man's combined auditing and record book, customer's receipt and identifying tag for the efficient and accurate management of such service man's business.

To attain these objects and such further 30 objects as may hereinafter appear or be pointed out, I make reference to the accompanying drawings forming a part hereof, in which—

Fig. 1 is a plan view of my device, with 35 the cover open to disclose the first page which is partially turned to expose the other parts thereof immediately underneath.

Fig. 2 is an end elevational view of my 40 book in closed position.

Fig. 3 is a perspective view of a tag and customer's receipt as they appear immediately after severing these parts.

The device provided by this invention has 45 particular applicability to a storage battery repair and rental service station. In such business it is customary to rent out to a customer the repairman's battery while the customer's battery is left for recharging, repair or other similar purposes. Under 50 such conditions it becomes necessary to keep a record with great accuracy of the storage battery so rented out and of the customer's battery, to prevent losses incidental to the accidental or intentional interchange of the 55 repairman's battery for the customer's battery. It also becomes necessary to keep an

accurate account of the repeated use of a rental battery in order that its life may be extended and best results obtained therefrom. With a device, such as contemplated 60 by the herein described invention, at a single writing a notation is made of the battery rented out by the repairman and is clearly and permanently recorded in volume form, at the same time means are provided 65 for recording the details or history concerning the customer and the car or vehicle from which the particular storage battery was taken and left for repair or recharging, and in which the rental battery was supplied. 70

With a construction such as herein contemplated, a single entry will obtain a permanent record and at one operation procure identical information on the customer's receipt or rental agreement and tag. For this 75 particular type of business, the tag is made of acid resisting material in order to prevent, as has heretofore been experienced, the defacing of such identifying tag by acid contents of the batteries. 80

Referring more particularly to the drawing, 10 is the original record sheet having a plurality of units 11, each unit having a combined receipt, rental agreement and battery history portion blank 12 and a customer's name and identifying form blank 13, that is, blank spaces being provided for filling in the details under the headings outlined thereon. This original sheet is superimposed upon a sheet 14 which has the exact 85 duplicate printed matter thereon, as the first sheet 10 forming units 15. The units of printed matter of the sheets 14 are preferably divided from each other by weakened lines of fold 16, preferably a series of perforations running transversely across the full width of the page and indented on the edge by notches 16'. Each unit 15 is in the form of a tag having an attaching eyelet 22 90 preferably reinforced by a washer 23 made of suitable reinforcing material and is divided transversely into three portions herein referred to as the binding strip portion 17, receipt portion or stub 18, and tag portion 19, by weakened lines of fold or perforations 20 and 21 respectively. The sheet 14 is preferably made of stiff paper which may be impregnated or treated to be substantially acid resisting in character. 100

Groups of sheets 10 and 14 of the series of units as above described, are superimposed with the sheet 10 overlying the sheet 14 so 105 110

that the printed matter of each coincides one above the other and are then bound in book form by stapling or otherwise, preferably including the same within a cover of 5 a stiffened back 24, a more flexible front cover 25 and binding edge fabric 26, all as shown stapled or stitched at 27.

The page 10 is preferably made of a shorter width than the page 14 and where 10 this page has the eyelets formed of added reinforcing material, the edge 28 thereof is made to just clear the row of eyelets 23 above described.

Superimposed pages of this nature can 15 thus be arranged without any disturbing bulge at one side of the book, as the reinforcing eyelets nest outside the edge 28 to barely add any additional thickness to this edge of the book. Other features of this 20 arrangement of parts will appear hereafter.

In use the units of each page 10 and 14 are each numbered in consecutive order as is shown by the bold-face characters, the receipt stub and tag portion corresponding 25 thereto having like numbers. A sheet of so-called carbon paper 29 is interposed between the sheets 10 and 14 with its recording surface arranged for recording on page 14. Whatever history or data is necessary is 30 then entered upon the original sheet 10 in the spaces or blanks therefor provided, in accordance with the particular system adapted. Impression is recorded in duplicate simultaneously upon the sheet 14 by means 35 of the carbon or recording paper 29 in a manner which will be apparent.

The tag 19 with its attached stub 18 is then separated from the book by tearing along the weakened lines of fold or row of perforations 16 and 20 and thereafter the stub 40 18 is separated from the tag along the weakened line of fold 21. Preferably this last step is only made after the attaching cord 30, which is provided therefor in the 45 eyelet 22, has been affixed to the article desired to be identified.

Continued use of the book in this manner and of the tags and receipt blanks until 50 complete disposal of the tags and receipts has been made, will leave in book form the original entries for record purposes, the repair and rentals made, as well as the original contractual obligation of the customer.

As above described, the original receipt 10 55 is made of a width shorter than that of the tag sheet 14, permitting of ready accessibility to the next place of entry on the tag sheet and with great facility permitting turn-

ing to such page. Thus in this way the extended length of the underlying tag sheet 60 serves in the nature of an index for the next place to make entries. This difference in length also permits of the nested arrangement of the eyelets of the tags so as to prevent an undue and cumbersome thickness 65 of the bound book. The arrangement of the eyelet at the open edge of the book also permits the insertion of the attaching cord 30 at the eyelet without disturbance of the remainder of the book, and in this manner 70 not only does it prevent any undue thickness of the book but the tag may be equally prepared for its necessary and intended purpose before the immediate transaction for which it is intended with great facility and 75 ease.

It will thus be observed that I have provided an arrangement whereby books and records may be kept at a minimum amount of manipulation, and at a single entry, the 80 office records, shop records and customer's receipt will be obtained. Also, in this manner an identifying tag or receipt may be obtained from the office or managing end of the business for the repair shop or customer with 85 the greatest dispatch and minimum of delay and handling.

It will be observed that though I have described my invention as having particular utility for storage battery repair and rental 90 men's business, I consider my invention as equally adaptable to other classes of business requiring similar parts and construction, and that minor changes in the form and arrangement of the various parts may be made 95 without departing from the spirit of my invention, the scope of which is set forth in the appended claim.

Having thus described my invention and illustrated its use, what I claim as new and 1 desire to secure by Letters Patent is—

A bound book comprising a group of 1 pages made up of a sheet divided by a plurality of weakened lines of fold into units comprising a binding strip, an owner's receipt check and an identifying tag having a reinforced eyelet and a superimposed duplicate sheet for permanent binding therewith in the form of a book, said duplicate sheet being of a shorter width than said first mentioned sheet, to permit said eyelets to nest beyond the edge thereof.

In witness whereof, I have hereunto signed my name.

AARON J. MIRSKI.
